UNITED STATES PATENT OFFICE

HENRY R. VOGEL, OF ARCADIA, WISCONSIN

MOTOR

Application filed February 28, 1930. Serial No. 432,062.

This invention relates to an internal combustion engine and while the invention might be applied to various types of such engines, it is illustrated particularly as applied to an engine of the stationary type or of the type in which the cylinders are stationary. Some of the problems encountered in constructing an internal combustion engine are securing a simple means for the distribution of the gases to the cylinders, securing compression and properly lubricating the motor.

It is an object of this invention to provide an internal combustion motor preferably of the two-cycle type which has stationary power and compression or booster cylinders, the combustible mixture being compressed in the latter and then delivered to the former.

It is another object of the invention to provide an internal combustion motor in which the usual movable valves together with their springs, rocker arms and tappets are eliminated.

It is another object of the invention to provide an internal combustion engine having a plurality of power cylinders and the same number of booster or compression cylinders, said cylinders having openings therein, conduits communicating with said openings, a casing to which said conduits lead and a rotatable member in said casing adapted to distribute a combustible mixture to the compression cylinders and also affording a passage for said mixture from the compression cylinders to the power cylinders.

It is still another object of the invention to provide an internal combustion motor having a plurality of power cylinders, the same number of compression or booster cylinders, a crank shaft, said power and compression cylinders being arranged in pairs disposed substantially at opposite sides of the crank shaft, said cylinders having openings thereinto, conduits communicating with said openings and communicating with a cylindrical casing concentric with the crank shaft, together with a rotatable member on the crank shaft adapted to have a combustible mixture delivered thereto and having means for delivering said mixture to the conduits leading to said compression cylinders, said mem-

ber having an internal passage affording communication between the conduits from the compression cylinders and the conduits connected to the power cylinders.

It is a further object of the invention to provide such a motor as set forth in the preceding paragraph which has a chamber surrounding said cylindrical casing adapted to contain the combustible mixture, said rotatable member having openings therein communicating with said chamber through which the combustible mixture is delivered to said rotating chamber.

It is more specifically an object of the invention to provide an internal combustion motor comprising, a power cylinder and a compression or booster cylinder cooperating therewith, said cylinders having pistons therein connected to a crank shaft, a cylindrical casing concentric with the crank shaft having ports leading to the power and compression cylinders, a rotatable member fitting in said casing having a peripheral recess to which a combustible mixture is delivered, said recess aligning at times with the conduit leading to said booster cylinder, said member also having an internal chamber with ports leading therefrom adapted to align at times respectively with the ports in said casing leading to the power and booster cylinders.

These and other objects and advantages of the invention will be fully set forth in the following description made in connection with the accompanying drawings, in which like reference characters refer to similar parts throughout the several views, and in which:—

Fig. 1 is a view in end elevation of the motor;

Fig. 2 is a section taken substantially on line 2—2 of Fig. 1 as indicated by the arrows;

Fig. 3 is a perspective view of a rotating distributing member used;

Fig. 4 is a diagrammatic view of a pair of the cylinders, the distributing member and casing in which it is mounted;

Fig. 5 is a view similar to Fig. 4 showing the parts in other positions, and

Fig. 6 is a view similar to Fig. 4 showing the parts in different positions.

Referring to the drawings, a motor is shown comprising a frame designated generally as 10, said frame having a substantially cylindrical portion from the periphery of which project circumferentially spaced hubs 10a. Cylinders 11 and 12 are secured in the hubs 10a, said cylinders being shown as having flanges 11a and 12a respectively, which seat on the tops of said hubs, said cylinders extending down into said hubs a considerable distance. While various means may be used to hold the cylinders in place, in the embodiment of the invention illustrated they are shown as having mutilated flanges 11b and 12b received in channels in the cylinders, the cylinders then being rotated to bring the flanges out of line with the channels. Cylinders 11 and 12 are illustrated as having cooling fins 13 thereon and cylinders 11 are shown as having openings or ports 11c adjacent their outer-ends. Cylinders 12 are shown as having inlet openings or ports 12c and exhaust ports or openings 12d. As shown in Fig. 1, there are two exhaust ports somewhat close together at one side of the cylinder and exhaust conduits 14 lead from these exhaust ports. The cylinders 12 also are shown as each having a pair of spark plugs 15 in their outer ends which plugs will be of the usual type and will be as usual connected to the timer or distributor. The frame 10 has an opening 10b of considerable size centrally thereof at one side and a side plate 16 is bolted to the frame 10 by the headed and nutted bolts 17. Plate 16 has a central hub 16a in the inner side of which is secured the ball bearing casing 18. Frame 10 has a large central opening at its side opposite the opening 10b which is covered by a manifold 19 having a flange bolted to frame 10 by the headed and nutted bolts 20. Member 19 has a central hub or cylindrical casing 19a at its center in the inner end of which is secured a ball bearing casing 21. Member 19 has an outer opening surrounded by an outwardly extending flange 19e and a member 22 covers said opening, the same having a peripheral flange bolted to the flange 19e by the headed and nutted bolts 23. Member 22 has a central hub portion 22a in which is secured a ball bearing casing 24. A housing member or shell 25 is bolted to member 22 by the headed and nutted bolts 25a and projects outwardly therefrom having its outer end open and provided with an outwardly extending peripheral flange 25b. An oil distributing casing 26 is secured to the end of member 25 having a flange bolted to flange 25b by the headed and nutted bolts 27. Member 26 has a central hub 26a having a central bore or recess therein which forms the bearing for the end of a crank shaft 28, portions of which are also journaled in bearings 18, 21 and 24. The member 19 has conduits 19b

extending therethrough having outwardly projecting hubs to which are connected conduits 29 in turn communicating with the openings 11c in the cylinders 11, said conduits being shown as being held in place by headed bolts 29a having their ends threaded in cylinders 11 respectively. Member 19 has other conduits 19c extending therethrough having oppositely projecting hubs to which are connected the conduits 30 which align with openings in frame 10, in turn aligning with the inlet openings 12c in cylinders 12, conduits 30 also being shown as being held in place by bolts 31 having their ends threaded into the frame. A piston 32 is disposed in each of the cylinders pivotally connected to the usual connecting rod 33 which in turn is pivotally connected to a head 34 of a master connecting rod 35. Each cylinder 12 has a piston 36 therein to one of which rod 35 is pivotally connected. The head 34 as shown in Fig. 2 comprises two laterally spaced disk-like members having bearings therein for the ends of the wrist pin 37, said disks also having secured therein at their outer sides ball bearing casings 38 in which the crank portion 28a of the crank shaft 28 is journaled. A counterbalance segment 39 extends at the side of the crank shaft opposite the crank portion 28a. Crank shaft 28 is shown as having adjacent its outer end and in member 25 a spiral gear 40 held in place by nuts 41 threaded on the crank shaft at either side of the same, which gear is arranged to drive the timing mechanism. Crank shaft 28 also has secured thereto within the casing 19a a gas distributing member 42. Member 42 is of cylindrical shape and is provided with an interior chamber 42a, said member having end openings fitting crank shaft 28 and being held in place on said crank shaft by a nut 43 engaging one end thereof. Member 42 has packing rings 44 extending circumferentially thereof adapted to engage the interior wall of casing 19a and form seals against the passage of gas longitudinally of member 42, at the periphery thereof. At the outer side of the outer ring 44 member 42 is provided with a peripheral segmental recess 42b and the same also has a plurality of holes 42c extending from its outer end into the recess 42b. Adjacent the rings 44 member 42 has ports 42d and 42e extending from its periphery to the chamber 42a. As shown in Fig. 2, recesses 42b and 42e align with the ports or openings in the casing 19a communicating with the conduits 19b and port 42a aligns with the openings or ports in casing 19a communicating with the conduits 19c. The frame 10 can be supported from any suitable support, a portion of a supporting member 45 being shown in Fig. 1. The chamber within member 19 is adapted to form a gas chamber or a chamber for the combustible mixture. In Fig. 1 a

carbureter 46 is shown connected to the lower portion of casing 19 which will deliver the gas into member 19, through the opening 19d shown in dotted lines in Fig. 2. Said carbureter 46 will be of any well-known type and need not be further described. A distributor 47 is shown in Fig. 1 which will be of any standard type, the same being shown as driven by a shaft 48 secured to a helical gear 49 meshing with gear 40. Shaft 49 also forms a driving means for an oil pump 50 from which a plurality of oil conveying tubes 51 are shown as leading, a pair of these being shown as extending into member 19 adapted 15 to lubricate member 42 and rings 44 and one of which is shown as extending to the end of the motor for lubricating bearings for the crank shaft. The oil pump 50 will be provided with an inlet line extending into a sump 20 chamber 52 which extends from the bottom of frame 10.

It will be seen that there is a cylinder 11 for each of the cylinders 12 and the cylinders 11 and 12 may be taken as arranged in pairs 25 which are at substantially opposite sides of the crank shaft. In operation the combustible mixture will be taken into the manifold 19. The chamber 19 will be supplied from the carbureter 46. The gas from this chamber 19 can pass through the openings 42c in member 42 and into the recess 42b. In Fig. 6 the piston 32 in a booster cylinder is shown as almost at the outer limit of its stroke. As the engine turns a little further piston 32 30 starts inwardly or away from the outer end of the cylinder giving a suction stroke. At this time the recess 42c comes into alignment with the port in casing 19a leading to conduit 19b and a charge of gas is drawn into 35 the booster cylinder through the conduit 19b. When piston 32 has come substantially to the end of its suction stroke member 42 has turned sufficiently for the end of recess 42c to pass the port leading to conduit 19b so that 40 communication with the booster cylinder is cut off and in a further movement of the engine piston 32 starts on its compression stroke and compresses the gas just taken in. When the piston 32 nears the end of its compression 45 stroke, the port 42e comes into alignment with the port leading to conduit 19b and port 42d comes into alignment with the port leading to conduit 19c. The gas which has been compressed in the booster or compression cylinder thus passes through conduit 19b, through port 42e into the chamber 42a in member 42 and out through the port 42d into conduit 19c and through the inlet port into the power cylinder 12. At this time the member 42 is in 50 the position shown in Fig. 6. At this time the piston in the power cylinder has just finished its power stroke and the inlet opening 12c is uncovered by the piston. The gas of course has been highly compressed in the 55 booster cylinder and it passes into the power

cylinder with great rapidity. The piston 36 in the power cylinder then begins its upward stroke and covers the inlet port 12c. The engine, as stated, is a two-cycle engine and the exhaust occurs as soon as the piston has gone far enough on the firing stroke to uncover the exhaust port 12d. As piston 36 moves toward the outer end of the cylinder the exhaust port is covered and the gas is compressed in the end of the cylinder until the charge is fired. Piston 36 in Fig. 5 is shown as having covered the inlet port but the exhaust port is still open. In Fig. 4 the piston 36 is shown as almost at the end of its compression stroke and substantially in firing position. The rush of gas into the cylinders 12 through the inlet ports will assist somewhat in expelling the burned gases through the exhaust port 12d and thus assists in the scavenging of the burned gases. The firing and boosting cylinders are arranged in pairs and the conduits leading thereto from casing 19a are equally distributed about said casing. The member 42 in its rotation will successively come into the same relation with each cooperating pair of firing and booster cylinders. The description given of this member in relation to one pair therefore will apply to its action with the other pairs. The timer will of course be adjusted to operate the spark plugs on each outward movement of the pistons 36, the timer, as stated, being driven from the crank shaft through the gears 40 and 49. Oil will be pumped by the pump 50 from the sump 52 and delivered through the various oil tubes 100 for oiling the moving parts.

From the above description it is seen that applicant has provided a very simple and efficient motor of the two cycle type comprising a plurality of stationary cylinders. The construction does away with all valves, springs, rocker arms, tappets and adjustments therefore and the same is thus simplified in a high degree. The motor is also entirely lubricated from inside of the crank case and lubrication is simplified. A high compression is obtained which adds to the efficiency of the motor. The distribution of the gas is made simple by the member 42 cooperating with the casing 19a and the parts leading therefrom. The motor therefore has comparatively few moving parts. It is obvious that the device will have a high degree of utility for the purpose intended.

It will, of course, be understood that various changes may be made in the form, details, proportions and arrangement of the parts, without departing from the scope of applicant's invention, which, generally stated, consists in a device capable of carrying out the objects above set forth, in the novel parts and combinations of parts disclosed and defined in the appended claims.

What is claimed is:—

1. An internal combustion engine having

in combination, a stationary power cylinder, a stationary compression cylinder co-operating therewith, said cylinders having openings leading thereto, conduits respectively connected to said openings, a casing with which said conduits communicate, a crank shaft passing through said casing, said conduits being off-set longitudinally of said crank shaft, said casing having ports opening into said conduits, a member revolvable with said crank shaft in said casing having a chamber therein and ports leading therefrom adapted respectively to align with said conduits, said member also having a recess in its periphery adapted to align with the conduit leading to said compression cylinder and a source of gas communicating with said chamber whereby gas can be supplied to said compression cylinder, compressed therein and then delivered to said power cylinder.

2. An internal combustion engine having in combination, a stationary power cylinder, a piston reciprocable therein, a crank shaft to which said piston is connected, said cylinder having an inlet opening thereinto, a stationary compression cylinder, a piston reciprocable therein and connected to the crank shaft, a conduit leading from the outer end of said compression cylinder, a conduit leading from said inlet opening of said power cylinder, a cylindrical casing concentric with the crank shaft and having ports with which said conduits communicate and a revolvable member in said casing connected for revolution with said crank shaft and to which the combustible mixture is delivered having means for delivering said mixture to said compression cylinder and means for affording communication between said conduits.

3. An internal combustion engine having in combination, a plurality of circumferentially spaced stationary power cylinders, a like number of stationary compression cylinders, the latter being arranged almost diametrically opposite the power cylinders, a crank shaft disposed substantially centrally of said cylinders, pistons in said cylinders respectively, said pistons being connected to said crank shaft, said power cylinders having inlet openings and exhaust openings, said compression cylinders having openings adjacent their outer ends, conduits extending from the intake openings of said power cylinders, conduits extending from the openings in said compression cylinders, a stationary cylindrical casing concentric with said crank shaft having ports with which said conduits respectively communicate, a rotary member connected to said crank shaft having a peripheral recess adapted to align with and cooperate with the conduits extending from said compression cylinders, means for delivering a combustible mixture to said recess,

said rotary member having a central opening and having ports leading therefrom adapted to cooperate with said first mentioned ports to afford communication between said conduits leading from a power cylinder to a corresponding compression cylinder.

4. The structure set forth in claim 1, a casing surrounding said cylindrical casing forming a combustible mixture chamber, said rotary member having openings through one end thereof leading to said recess and communicating with said chamber through which said combustible mixture passes.

5. An internal combustion engine having in combination a crank shaft, a stationary power cylinder, a stationary compression cylinder oppositely disposed and co-operating therewith, said cylinders being disposed radially of the axis of said crank shaft and having openings leading thereto, conduits respectively connected to said openings, a central casing with which said conduits communicate, pistons working in said cylinders and connected with said crank shaft, said conduits and casing being offset longitudinally from said cylinders, a valve member revolvable with said crank shaft and disposed within said casing and having ports therein adapted to align respectively with said conduits, and a source of gas communicating with said member whereby gas may be supplied to said compression cylinder, compressed therein and then delivered to said power cylinder.

In testimony whereof I affix my signature.
